UNITED STATES PATENT OFFICE.

HARRY K. V. TOMPKINS, OF TAMPICO, MEXICO.

CASING HANDLING AND SUSPENDING APPARATUS FOR WELLS.

Application filed December 1, 1921. Serial No. 519,142.

To all whom it may concern:

Be it known that I, HARRY K. V. TOMPKINS, a citizen of the United States, residing at Tampico, in the Republic of Mexico, 5 have invented certain new and useful Improvements in Casing Handling and Suspending Apparatus for Wells, of which the following is a specification.

This invention relates to casing handling and suspending apparatus for wells and it comprises in general a split or segmental ring or sleeve with its lower end resting on an outer shell or nipple, such shell or nipple so designed and constructed that it can be 10 mounted on the casing of the well being drilled while suitable valves, pipes or other apparatus desired, may be mounted on the upper end, the split or segmental sleeve being provided with means for opening and closing it and having an interior diameter at 15 the top when in closed position larger than the exterior diameter of casings to be suspended or lowered but smaller than a collar or nipple used for uniting ends of casings to 20 be lowered, whereby the lower edge of the collar or nipple may rest on the top of the split or segmental ring or sleeve and whereby when the ring or sleeve is opened the collar with attached casings may be lowered or raised through the sleeve and in the 25 well; all as more fully hereinafter set forth and as claimed.

The invention primarily relates to apparatus to be used on the casing of the well being drilled and it is particularly useful 35 in the drilling of oil or gas wells.

Among other objects of the invention is the provision of an apparatus which will prevent leakage of fluid, gas or vapors past 40 the casing being set, the provision of an apparatus simple in construction and operation and so designed that one or more joints of the casing may be removed or lowered or additional casing added readily and with 45 a saving of time and labor. Other objects of the invention will hereinafter appear.

In the accompanying drawings showing 50 one form of a specific embodiment of my invention, and in the several views of which similar numerals designate corresponding parts,

Fig. 1 is a vertical section through my casing handling and suspending apparatus, parts being shown in elevation;

Fig. 2 is a top plan view partly in section

with the collar and casing of Fig. 1 removed;

Fig. 3 is a bottom plan view of the interior sleeve and

Fig. 4 is a segmental section showing the 60 split sleeve open or retracted and in a position permitting the lowering or raising of casings in the well.

In the drawings, 1 indicates the lower part of a steel shell having interior threads 65 by means of which it may be mounted upon the casing (the casing not shown) of the well being drilled. The upper end of this shell has outwardly flaring upper portion 2 and the straight top 3 provided with exterior 70 threads. A similarly shaped shell 4 having interior screw threads at its lower end is attached to the first shell and is provided at its top with screw threads for the attachment of a gate valve, pipe or other apparatus 75 usually used and as may be desired.

The flaring portion 2 of the lower shell has a smooth interior wall as at 5 which may be ground for the purpose of making a tight joint with the bottom of the split 80 sleeve to be hereinafter described.

The split sleeve 6 may be made in three parts each of which comprises a curved section of metal having the preferably integral outwardly and downwardly extending 85 flanges 7 slotted at 8 for the purpose of receiving and retaining the heads of the bolts 9. Each one of these bolts (3 being shown) is threaded through the upper portion of the lower shell as at 10 and each is provided with a square head 9' by means of which it may be drawn outwardly or forced inwardly with respect to the shell and by means of which it may move a segment of the split sleeve 90 either direction as the case may be. Nut 11 95 locks bolt 9 in any position desired.

Each section of the split sleeve is provided at its bottom with the beveled face 12 ground so as to make a tight joint with the side 5 of the shell, and at their upper ends each of the segments of the sleeve 6 is provided with the ground beveled face 13 adapted to make a tight joint with a complementary face on the collar to be hereinafter described.

Near the upper part of the lower shell I provide a ring 14 having a plurality of depending flanges 15 (3 being shown), these flanges being used for securing the ring to 100 the upper portion of the lower shell by 105 110

means of the bolts 16. The outer periphery of the ring may extend slightly beyond the flange and the upper portion of the lower shell may be provided with a shoulder 17 in order that the ring may be supported and trued in the shell. The interior of this ring 14 is not a true circle, it being provided with the 3 inset portions 18 corresponding in contour to the outer surfaces of the segments of the split ring or sleeve 6. And since it is desirable to hold rigidly the upper portion of the segments against the interior of the ring 14 when the segments are expanded or opened, the interior face of the ring is beveled slightly as is shown in dotted lines in Fig. 3 (this being a bottom plan view). This ring 14 is of sufficient internal diameter to permit the expansion of the segments of the sleeve a sufficient distance to allow the collar and the casing to be raised or lowered therethrough.

The casing 19 to be lowered or raised in the well is screw threaded at its upper end and is supported by screw threaded collar 20 having at its lower end a beveled face 21 complementary to the face 13 of the segments of the split sleeve so that a tight joint is made at this point. When the split sleeve is in closed position its internal diameter at the top is less than the external diameter of the collar 20, while the external diameter of the casing 19 to be lowered or raised, or indeed suspended in the well, is slightly less than the internal diameter of the closed split sleeve. This construction permits suspending the casing 19 in the well by means of the collar 20 having its face 21 resting on the face 13 of the split sleeve. The collar has reverse threads at its upper end. The split sleeve may be opened a sufficient distance to permit the collar 20 to pass through.

A tight joint is made between the seat 5 of the lower shell and the beveled end 12 of the split sleeve and a tight joint is made between the beveled face 13 of split sleeve at the top and the beveled face 21 of the collar at the bottom so that in closed position there is no leakage of fluid, gas, or vapors from the well around the casing or otherwise. When the split sleeve is opened or expanded through turning the bolt 9, the lower end 12 of each segment rocks, so to speak, upon a seat 5 in the lower shell but does not move totally away therefrom.

The operation of the apparatus is obvious from foregoing description. It may be used as a well casing head near the ground to hold the inner casing while sections are being connected or detached. The casing in the well may be raised or lowered while a tight joint is maintained between the split sleeve and the lower shell 5 and that while the casing is suspended in the well there is no opportunity for leakage of fluid, gases or vapors. Also the casing can be lowered

at any time and without the necessity of raising it as is the practice with all other devices of this character as used at present. The apparatus is extremely simple in construction and operation and consists of a relatively few number of parts as compared with other devices known to the applicant and heretofore used. It is not necessary to use any packed joints which in some instances are likely to be attacked by the vapors and gases from the well and it is not necessary in raising or lowering a casing with the use of my apparatus to remove any parts. It is only necessary to suspend the casing to be lowered, open the segments of the split sleeve, lower the casing until the collar rests above the top of the split sleeve, close the split sleeve, and allow the bottom of the collar to rest on the top of the split ring. Various modifications may be made without departing from the spirit or scope of my invention as set forth in the appended claims. The split sleeve may be made in any number of segments, three being shown for the purpose of illustration. I deem it advisable to make all the parts of steel. The apparatus is self-contained and easily installed and capable of withstanding the most severe conditions continually without depreciation. By the use of this apparatus the well may be drilled positively and with safety while the casing which is to be used is suspended in the hole.

The split sleeve constitutes means for supporting the collar and the plurality of sections of the split sleeve form a tube when the parts are in closed position, such tube tapering outwardly in a downward direction. When closed this sleeve is circular in cross section.

What I claim is:—

1. Casing handling and suspending apparatus for wells, comprising a chamber with means at its lower end for attachment to the casing of a well, a supporting split sleeve substantially circular in cross section in the chamber having its lower end resting on the wall of the chamber and means for opening and closing said split sleeve, a collar for supporting casings to be raised or lowered in the well, said collar having an external diameter greater than the internal diameter of the top of the split sleeve when closed, and a casing of less external diameter than the closed sleeve, said casing supported by the collar.

2. Casing handling and suspending apparatus for wells, comprising a chamber with means at its lower end for attachment to the casing of a well and with means at its upper end for attachment of well equipment apparatus, a supporting fluid tight split sleeve in the chamber having its lower end resting on the wall of the chamber and means for opening and closing said split

- sleeve, a collar for supporting casings to be raised or lowered in the well, said collar having an external diameter greater than the internal diameter of the top of the split sleeve when closed, and a casing of less external diameter than the closed sleeve joint, said casing supported by the collar.
3. Casing handling and suspending apparatus for wells, comprising a chamber with means at its lower end for attachment to the casing of a well, a supporting fluid tight split sleeve substantially circular in cross section in the chamber having a lower beveled end resting on the wall of the chamber and means for opening and closing said split sleeve, a collar for supporting casings to be raised or lowered in the well, said collar having an external diameter greater than the internal diameter of the top of the split sleeve when closed, and a casing of less external diameter than the closed sleeve supported by the collar.
4. Casing handling and suspending apparatus for wells, comprising a chamber with means at its lower end for attachment to the casing of a well, a supporting fluid tight split sleeve in the chamber having its lower end resting on the wall of the chamber and having a beveled upper end, means for opening and closing the split sleeve, a collar for supporting the casing to be raised or lowered in the well, said collar having its lower end provided with a face adapted to engage the beveled end of the split sleeve and having an external diameter greater than the internal diameter of the top of the split sleeve when closed and a casing of less diameter than the closed sleeve supported by the collar.
5. Casing handling and suspending apparatus for wells, comprising a chamber with means at its lower end for attachment to the casing of a well, a split sleeve in the chamber having its lower end resting on the wall of the chamber, each of the split sections of said sleeve having means for engagement of a bolt, a bolt in engagement with said means and extending through the wall of the chamber, and means for operating the bolt to open or close the said split sleeve, a collar for supporting casings to be raised and lowered in the well and a casing secured to said collar.
6. Casing handling and suspending apparatus for wells, comprising a chamber with means at its lower end for attachment to the casing of a well, a split sleeve in the chamber having its lower end resting on the wall of the chamber and said split sleeve comprising a plurality of sections each provided on its outer face with a downwardly extending slotted flange, a headed bolt having its stem extending through the slot of the said flange and being threaded through the wall of said chamber, and means for operating said bolts whereby the split sleeve may be opened and closed, and a collar adapted to hold the casings having its lower edge resting on the upper edge of the said split sleeve when closed.
7. Casing handling and suspending apparatus for wells, comprising a chamber provided at its lower end with means for attachment to the casing of a well, a split sleeve supported in said chamber with its lower end resting on the wall thereof and means for opening and closing the section of said split sleeve, means secured to the walls of said chamber for limiting the outward movement of the sections of said split sleeve, and a collar having its lower end resting on the top of said split sleeve when in closed position.
8. Casing handling and suspending apparatus for wells, comprising a chamber with means at its lower end for attachment to the casing of a well, a supporting split sleeve in the chamber having its lower end resting on the wall of the chamber and means for opening and closing said split sleeve, a screw threaded collar for supporting casings to be raised or lowered in the well, said collar having an external diameter greater than the internal diameter of the top of the split sleeve when closed, and a casing of less external diameter than the closed sleeve supported by the collar.
9. Casing handling and suspending apparatus for wells, comprising a chamber with means at its lower end for attachment to the casing of a well, collar supporting means in said chamber comprising a plurality of sections arranged to be opened or closed and when in closed position being circular in cross-section, a collar having its lower end supported by the top of said collar support when in closed position, and a casing supported by said collar in said collar supporting means.
10. Casing handling and suspending apparatus for wells, comprising a shell having means at its lower end for attachment to the casing of a well and having outwardly flaring side walls and having means at its upper end for attachment of an enclosing shell, a second or enclosing shell secured to the first shell at the top thereof and having means at its top for attachment of well equipment apparatus, the two shells in assembled position forming a chamber, a split sleeve having its lower end resting on the flared wall of the first shell and provided with means for opening and closing the several parts thereof, the interior diameter of the said sleeve when in closed position being larger than the exterior diameter of casings to be suspended or lowered, a casing to be suspended or lowered through the sleeve and a collar on the casing of exterior diameter larger than the interior diameter of the sleeve when closed, whereby the collar

may support the casing inside the sleeve when the sleeve is closed and whereby the collar with the casing may be lowered through the sleeve and thus down into the well when the sleeve is opened.

11. Casing handling apparatus comprising a chamber arranged to be attached to the casing of a well, a sectional support in said chamber for casing holding means, casing holding means supported on said support and means extending through the wall of the chamber for spreading the sections of said support to allow the casing holding means to pass therethrough.

12. Casing handling apparatus comprising a chamber arranged to be attached to the casing of a well, a sectional support in said chamber for casing holding means, casing holding means supported on said support, means extending through the wall of the chamber for spreading the sections of said support to allow the casing holding means to pass therethrough and means in the chamber encircling said sectional support and limiting the outward movement of its sections.

13. Casing handling and suspending apparatus for wells comprising a chamber arranged to be attached to the casing of a well,

said chamber having inclined interior walls 30 ground to a true surface, a sectional support for casing carrying means in said chamber, the lower ends of the sections having ground surfaces adapted to engage and make a tight joint with the ground interior walls 35 of said chamber, casing carrying means supported on said sectional support and means for spreading the sections of said support apart to allow the casing carrying means to pass therethrough, the ground 40 lower end of the said sections of the support and the ground interior walls of the said chamber making a tight joint when the said sections are in their spread or closed position.

14. A swing-nipple construction for well casings comprising a coupling having an internal diameter larger than the outer diameter of the well casing, a bushing made up of segments pivotally supported inside the coupling to swing inwardly to engage the well casing or outwardly to release the same, and means adjustable to cause said segments to positively engage or to release the casing.

In testimony whereof, I have hereunto affixed my signature.

HARRY K. V. TOMPKINS.
